UNITED STATES PATENT OFFICE

167,491

ADJUSTABLE CHAISE

James C. Witty, Troy, Ohio, assignor to The Troy Sunshade Company, Troy, Ohio, a corporation of Ohio

Application October 12, 1951, Serial No. 16,918

Term of patent 14 years

(Cl. D15—11)

To all whom it may concern:

Be it known that I, James C. Witty, a citizen of the United States of America, residing at Troy, in the county of Miami and State of Ohio, have invented a new, original, and ornamental Design for an Adjustable Chaise, of which the following is a specification, reference being had to the accompanying drawing, forming a part thereof.

Fig. 1 is a view in perspective of an adjustable chaise showing my new design as it appears in one position of adjustment; and

Fig. 2 is a perspective view from the opposite side showing the chaise in a different position of adjustment.

I claim:

The ornamental design for an adjustable chaise, substantially as shown and described.

JAMES C. WITTY.
